[57] **CLAIM**

The ornamental design for a combined vehicle elevating roof and enclosure unit, substantially as shown and described.

DESCRIPTION

FIG. 1 is a side elevational view of a combined vehicle elevating roof and enclosure unit showing my new design;

FIG. 2 is a side elevational view thereof opposite to that shown in FIG. 1; and

FIG. 3 is a front end elevational view thereof, the rear end being substantially a mirror image of the front end shown herein.
